PAPER SUPPORTING AND FEEDING APPARATUS

Oscar J. Sundstrand, Bridgeport, Conn., assignor to Underwood Elliott Fisher Company, New York, N. Y., a corporation of Delaware

Continuation of application Serial No. 508,106, January 12, 1931. This application September 24, 1936, Serial No. 102,442

36 Claims. (Cl. 197—127)

This invention relates to the work-supporting devices of typewriting and bookkeeping machines. It relates particularly to means whereby two sheets, one of which may be termed a journal, tally or record sheet, the other being a ledger sheet or the like, may be independently supported and fed, and thereby the ledger sheet may be expeditiously and accurately positioned in the machine.

10 A particular object of the invention is to render possible the convenient insertion of a ledger sheet in front of the platen of a machine of the type in which the platen is not movable into and out of operative position.

15 In the accompanying drawings,

Fig. 1 is a front view of a paper carriage equipped with a device embodying the features of my invention, the view being broken away in the middle to shorten it.

20 Fig. 2 is a fragmental perspective view of a machine equipped with a carriage embodying the invention.

Fig. 3 is a longitudinal section through a winding drum comprised in the construction.

25 Fig. 4 is a section on line 4—4 of Fig. 3.

Fig. 5 is a section on line 5—5 of Fig. 3.

Fig. 6 is a fragmental detail view of one of the paper-feeding tapes and a clip positioned thereon.

Fig. 7 is a section on line 7—7 of Fig. 1.

30 Fig. 8 is a detail view taken approximately in the plane of line 8—8 of Fig. 1.

Fig. 9 is a perspective view of the lower end of one of the paper-feeding tapes.

Fig. 10 is a section on line 10—10 of Fig. 1.

35 Fig. 11 is a fragmental sectional view of the means for controlling the action of the pawl 22.

Fig. 12 is a view of the means for regulating the effective length of the stroke of said pawl.

Fig. 13 is a view similar to the lower portion 40 of Fig. 10, but showing the parts in another position.

Fig. 14 is a section on line 14—14 of Fig. 1.

Fig. 14a is a detail view of the pawl 73 and finger 79.

45 Fig. 15 is a view taken approximately in the plane of dotted line 15 of Fig. 1.

Fig. 16 is a fragmental right-hand side elevation of the machine.

This application is a continuance of an application filed by me on Jan. 12, 1931, Serial No. 508,106, for improvements in paper supporting and feeding apparatus.

In the particular embodiment which has been selected to illustrate the invention, the paper carriage comprises a longitudinal main frame mem-

ber or casting 1 to the ends of which are secured plates 2 and 3. The means for supporting the journal, record or tally sheet A and the carbon sheet B comprises a cylindrical platen 4 which is fixed to a shaft 5 that is journaled in bearings in 5 the end plates 2 and 3. The journal sheet A and the carbon sheet B are fed to the platen from the rear thereof, and for this purpose there is provided an apron 6 formed of two sheet metal plates secured to the frame member 1 and the end plates 10 2 and 3 so as to extend in an upwardly and rearwardly inclined position with the lower edge of the apron adjacent to the rear side of the platen 4.

Two guides 1 for the side edges of the sheets A and B are adjustably secured to the apron 6. 15

Means of any preferred construction may be used to hold the sheets A and B in contact with the platen 4. Herein I have shown a plurality of pairs of feed rolls 8 and 9, each pair being mounted in a support 10 which is pivoted at 11 20 to an arm 12 that is fulcrumed on the carriage at 13. A tension spring 14 normally presses the feed rolls toward the platen. The space between the feed rolls 8 and 9 is bridged by a plate 15.

The means for rotating the platen 4 may par-

take of various forms. Herein I have shown a finger wheel 17 secured to each end of the shaft

of the platen 4. Means may also be provided for rapidly rotating the platen 4 to inject and eject the sheets A and B. The form of ejector means 30

herein shown comprises a pinion 18 (Fig. 1) which is mounted upon the shaft 5 and which is ar-

ranged to be connected thereto by means of a clutch 18a.

The pinion 18 meshes with a spur gear 19 (Fig. 10) which is rotatably mounted

35 upon a stud 20 fixed upon the end plate 3. A

hand lever 21 is pivoted upon the stud 20 and

carries a pivoted pawl 22 that is arranged to en-

gage the teeth of the gear wheel 19. When the

hand lever 21 is in its initial or rearward position

40 (as shown in Fig. 10) the pawl 22 is held up out

of engagement with the gear wheel 19 by means

of a pin 23 which is secured to the pawl 22 and

extends through an opening 24 (Fig. 1) in the

hand lever. On the end of said pin is a rubber

45 buffer 23a. An abutment 25 (Figs. 1 and 12) for

the buffer 23a is adjustably mounted upon the end

plate 3.

A tension spring 26 connected to the hand lever 21 and anchored to a pin 27 on the

end plate 3 normally holds the lever 21 in its

initial position with the buffer 23a against the

abutment 25. An arm 28 is pivoted on the stud

20 to turn with some friction. In the free end of

said arm is a slot 29 into which extends a projec-

tion 30 on the pawl 22. When the hand lever 21

55

is pulled forward, the lagging of the arm 28 causes the pawl to swing down into engagement with the gear wheel 19, continuing movement of the handle lever causing the platen 4 to be rapidly rotated to feed the sheets A and B into or out of the machine. Forward movement of the handle 21 is limited by a stop 30°.

10 The ledger sheet, statement sheet or other work-piece C is fed into printing position from in front of the platen. The means provided for that purpose comprises a roll or winding means 31 which extends parallel with and below the platen 4. In this instance the roll 31 is shown as of approximately the same length as the platen 15 4. The roll 31 is fixed upon a shaft 32 which is journaled in the end plates 2 and 3. To the roll 31 are secured a plurality of tapes 33, four such tapes being herein shown. In order that the tapes shall be adjustable lengthwise of the 20 paper carriage in accordance with the width or location of the sheet C, the lower ends of the tapes are adjustably connected to the roll 31 by means herein shown as consisting of hooks 34 engaging the wall of a slot 35 extending longitudinally of 25 the roll 31.

The tapes extend upwardly in front of a guide rod 36 which is secured to the end plates 2 and 3 and thence upwardly past the platen 4. The upper end of each tape is attached to a winding drum 37 which is mounted upon a shaft 38 by means of a connection permitting the drum to be slid lengthwise of the shaft to correspond to the setting of the hooks 34. The winding drum is also yieldingly connected to turn with the shaft. The form of connection herein shown comprises a sleeve 39 (Fig. 3) slideable lengthwise of the shaft 38, but having a key 40 fitting in a keyway 41 in the shaft. The winding drum is rotatably mounted on the sleeve 39 and is yieldingly connected thereto by means of a coiled torsion spring 42, one end of the spring being fastened to the winding drum and the other being attached to a flange 43 on the sleeve. The spring tends to turn the drum in the direction to wind up the tape. To hold the sleeve in the position to which it has been adjusted along the shaft, I provide a collar 44 surrounding the sleeve 39 and having a peripheral groove 45. Approximately one-half of the bottom of the groove is cut away to accommodate a semicircular brake shoe 46 that lies in a semicircular recess 46^a in the sleeve 39. A contractile spring 47 lying in the groove 45 presses the brake shoe against the shaft 38. The shoe is of sufficient radial thickness to extend into the groove 45 (see Fig. 3) and thus serves to hold the collar 44 against endwise movement on the sleeve 39. The winding drum is held between the flange 43 and the collar 44.

The shaft 38 is rotatably mounted in a rigid frame 48 consisting of two arms 49 and a tie rod 50. The arms 49 are pivoted to the end plates 2 and 3 at 51. Rubber-covered rolls 52 are mounted upon the shaft 38 for adjustment longitudinally of the shaft. A rubber-covered roller 53 is rotatably mounted in the end plates 2 and 3, said roller being of approximately the same length as the platen. The frame 48 is normally held in its rearward position with the rolls 52 in contact with the roller 53 or a ledger sheet C resting against said roller by means of a spring 54 (Fig. 15) which is anchored to the end plate 2 at 55, the other end of said spring being connected to a hook 56 that is pivoted on the end of the rod 50. When a ledger sheet is to be inserted into the machine, the operator pulls the frame 48 for-

ward by taking hold of the tie rod 50, the forward movement of the frame being limited by engagement of the hook 56 with a stud 57 on the end plate 2.

Means is provided on the tapes 33 to form stops 5 against which the lower edge of the ledger sheet C may be positioned by the operator. The means herein shown for this purpose consists of sheet-metal clips 58 through which the tapes 33 are threaded. The clips are slightly curved so that 10 their upper edges diverge from the tapes sufficiently to provide space for the reception of the lower edge of the ledger sheet (see Fig. 6).

The means for operating the tapes comprises a finger wheel 59 fixed upon the right-hand end of the shaft 32 of the roll 31. By rotating the finger wheel in the counter-clockwise direction (as viewed in Fig. 7), the roll 31 will be rotated in the direction to wind up the tapes 33 thereon and thus feed the ledger sheet C downwardly and around the roll 31. 60 is a curved guard plate fixed in the carriage and extending partially around the roll 31.

The means for causing the roller 53 to rotate with the roll 31 comprises a flexible inextensible band 61 (Figs. 1, 7 and 8) the lower end of which is secured to the left-hand end of the roll 31, and the upper end of which is secured to a roll 62 which is fixed upon the shaft 38. Intermediate its ends the band 61 extends over a roll 63 which is rigid with the left-hand end of the rubber-covered roll 53. The course of the band 61 is best shown in Fig. 8. When the finger wheel 59 is turned to draw the tapes 33 downwardly, the rubber-covered roll 53 is rotated in the same direction through the action of the tapes in turning the shaft 38 in the direction to wind up the band 61 on the roll 62, the friction of said band on the roll 63 causing the roll 53 to turn. When the finger wheel 59 is turned in the opposite direction, the band 61 is wound up on the roll 31, whereby the roll 53 is rotated in the direction to feed the ledger sheet upwardly, and the shaft 38 is rotated in the direction to wind up the tapes on the drums 37. The spring connection between the drums and the shaft 38 compensates for variations in the thickness of the windings on said drums as the tapes are wound up and unwound.

Means may be provided for rapidly rotating the roll 31 and hence the roll 53 in either direction. The means herein shown for this purpose comprises a gear 64 (Fig. 16) pivotally mounted on the end plate 2 and having a hand lever 65 fixed rigidly thereto. The gear wheel 64 meshes with an intermediate gear wheel 66 which is rotatably mounted on the end plate 2 and which in turn meshes with a pinion 67 which is arranged to be connected to the shaft of the roll 31 by means of a clutch 68. When the pinion 67 is clutched to the shaft of the roll 31, a forward pull upon the handle 65 will cause the roll 31 to be rotated in the direction to draw the ledger sheet C downward to bring the line on which entries are to be made to the printing position or approximately so. A rearward push upon the handle 65 will cause the roll 31 to be revolved in the direction to eject the ledger sheet. The rearward or initial position of the handle 65 is determined by contact of said handle with a stop 68' on the carriage 1, the clips 58 being then directly in front of the platen. The extent of the forward movement of the handle 65 is limited by engagement of said handle with the stud 51. When the handle is against the stud 51, the top line on the ledger sheet is in position to be printed upon. When inserting a ledger sheet on 75

which there are one or more lines of entries, the handle is pulled just far enough to bring the next line into position, accurate adjustment, when necessary, being made by declutching the pinion 67 and turning the finger wheel 59. In Figs. 2 and 14, the handle is shown in an intermediate position.

Means may be provided for turning the platen 4 and the roll 31 through one line-space movement in each cycle of operations of the machine. The means herein shown for this purpose comprises a universal rod 69 (Fig. 14) which is fixed at its ends to two arms which take the form of plates 70 and 71. The universal rod 69 and the plates 70 and 71 are rigidly secured to a pivot rod 72 (Fig. 7) which is mounted to turn in the end plates 2 and 3. A pawl 73 is pivoted upon the plate 70 at 74 and is urged toward a ratchet wheel 75, fixed to the pinion 67, by means of a spring 76. 77 (Fig. 15) is a spring-actuated lever carrying a roller that engages the teeth of the ratchet wheel 75 to prevent overthrow of the roll 31 and to locate the roll in definite angular position.

To prevent the automatic line-space mechanism from turning the roll 31 too far, I provide on the gear wheel 66 (Fig. 14) a pin 78 arranged to engage a finger 79 attached to the pawl 73. When the handle 65 is in its forward position (the ledger sheet being then in position for writing on the top line), the pin 78 is in the dotted position shown in Fig. 14. As the line-space mechanism operates to raise the ledger sheet the pin 78 travels around until, as the handle reaches its starting position, said pin engages the finger 79 and thus holds the pawl 73 away from the ratchet wheel 75. The finger 79 is shaped, as shown in Fig. 14a, so that the pin 78 shall engage only the end thereof.

On the plate 71 (Fig. 10) is pivoted at 80 a pawl 81 which is urged by a spring 82 toward a ratchet wheel 83 which is rigid with the pinion 18. 84 is a stop lug on the plate 71 to limit the action of the spring 82. A tension spring 85 connected to the plate 71 and to the pin 27 tends to swing the universal bar 69 rearwardly, the action of said spring being limited by contact of the plate 71 with a pin 86 on the end plate 3. When the bar 69 is swung forward, the pawl 81 engages a tooth of the ratchet wheel 83 and thus turns the platen 4 to effect line-spacing of the sheets A and B.

In every cycle of operations of the machine the universal rod 69 is moved forward by means herein shown as consisting of a lever 87 (Fig. 16) which is pivoted in the machine frame at 88. Said lever comprises an upwardly extending arm 89 carrying a roller 90 that bears at all times against the universal rod 69. The lever 87 is connected by means of a link 91 to a cam arm 92 which is pivoted in the machine frame at 93. The cam arm 92 is operated by a roller stud 94 carried by an arm 95 that is fixed to the main rock shaft 96 of the machine.

Means of any desired nature (none being herein disclosed) may be employed to disable the automatic line-space mechanism except at desired times, so that line-spacing normally shall not occur except at the end of a line.

A paper table 97 (Fig. 7) is pivotally mounted near its lower edge upon pivot pins 98 on the inner side of the end plates 2 and 3. Fixed to each end 70 of the paper table 97 is a rearwardly extending arm 99 having a rubber-covered stop portion 100 (Fig. 16) arranged to be normally held in contact with the forward side of the apron 6 by means of tension springs 101 connected to said arms 99 and 75 to anchorages 102 on the end plates 2 and 3. The

paper table 97 is provided with laterally adjustable side edge guides 103 which are secured in desired position by means including clamping screws 104. The paper table 97 is pivotally supported, as described, in order that it may be swung forward to give the user convenient access to the securing means for the guides 103. Contact of said guides with the rod 50 limits forward movement of the paper table 97.

It will, of course, be understood that the invention may be employed in connection with the handling of various kinds of work-pieces. The present drawings illustrate a journal sheet A, a carbon sheet B and a ledger sheet C, but, if desired, the two sheets on which printing is to be done may be only partially overlapped, the left-hand portion of the rear sheet A being left exposed to receive imprints, and the use of carbon paper dispensed with. Assuming that the work-pieces are arranged as shown in the drawings, the operation is as follows:

The journal sheet A and the carbon sheet B are inserted in the machine in the usual manner, said sheets being fed around the platen from the rear, and the normally upper end thereof passed under the roll 53, as shown in Fig. 7. In thus inserting the sheets A and B, the platen 4 is rotated by means of the handle 21, supplemented, if necessary by the use of the finger wheel 17. The operator then takes hold of the rod 50 and pulls the frame 48 forward into the position shown in dotted lines in Fig. 15, thus separating the winding drums 37 and the rolls 52 from the roll 53. The operator then inserts the ledger sheet C into the space between the winding drums 37 and the rolls 52 on the one hand and the roll 53 on the other, the lower edge of the ledger sheet coming to rest in the spaces between the clips 58 and the tapes 33. When the operator releases the rod 50 the spring 54 draws the frame 48 rearwardly to place the rolls 52 in contact with the ledger sheet and hold the latter in contact with the roll 53. The operator then draws the handle 65 forward as far as may be necessary to bring into approximate 45 position the line on which entries are to be made, the finger wheel 59 being used to locate said line accurately with respect to the printing line on the platen 4. The operator then proceeds to enter the date, folio number, items and balances 50 in the usual manner, the paper carriage moving from one columnar position to the next, and automatic line-spacing occurring at the end of the line so as to feed the journal sheet A and the carbon sheet B into position to receive the next 55 line of entry. Ordinarily, only one line of entries is made on the ledger sheet, but if more than one horizontal line of imprints is to be made the line-space mechanism 73, 75 operates to line-space the sheet C, excessive line spacing being 60 prevented by the operation of the pin 78 on the finger 79.

After postings have been made upon the ledger sheet, it is removed and another inserted, the journal sheet and carbon sheet remaining in the 65 machine until the journal sheet is filled or until a predetermined portion of the ledger posting has been done.

The roll 53 is slightly larger in diameter than the roll 63, hence the peripheral speed of the roll 70 53 is slightly greater than the speed of the tapes. Consequently, if the operator does not insert the sheet with its lower edge exactly horizontal (said edge being in contact with only one of the stops 58) the rotation of the roll 53 will cause 75

the part of the sheet that is not in contact with the other stop 58 to advance slightly faster until the sheet is in engagement with both stops.

If the system of bookkeeping calls for the entry of items on the customer's monthly statement at the same time that items are posted to the customer's ledger sheet, the ledger sheet and the statement sheet will be inserted in front of the platen, side by side. The extent to which 10 said sheets are inserted by the operator will be such that when the injector 65 is operated, the sheets will be fed into position for printing upon the proper line.

The distance between the bottom edge of the 15 ledger sheet and the line to be printed upon will usually be different from the distance between the bottom edge of the statement sheet and the line to be printed on. It will therefore be understood that said sheets will ordinarily be inserted 20 different distances, only one of the sheets being inserted into engagement with the stops 58.

It will be seen that the construction herein shown facilitates the insertion of the ledger sheet in upright position in front of the platen with the 25 face of the ledger sheet toward the operator, and that this result is attained without movement of the platen out of operative position. Since the platen is not movable transversely of its axis, it is described in some of the following 30 claims as being mounted on a fixed axis.

I claim as my invention:

1. The combination of a platen, sheet-introducing means adapted to receive the leading edge of a sheet at the rear of the platen and 35 feed the sheet around the front thereof, another sheet-introducing means for advancing a sheet downwardly from above the platen, the second said means including a guide which acts upon the leading edge of the second said sheet tending 40 to laterally align the same and direct it down past the front of the platen in close proximity thereto.

2. The combination of a platen, sheet-introducing means adapted to receive the leading edge 45 of a sheet at the rear of the platen and feed the sheet around the front thereof, another sheet-introducing means for advancing a sheet downwardly from above the platen, the second said means including a guide which tends to laterally 50 align the leading edge of the sheet and direct it down past the front of the platen in close proximity thereto, and the second said means being adapted for reverse operation to eject the sheet.

3. The combination of a platen, means for 55 feeding a sheet from the rear of said platen around the front thereof, feed rolls located above the platen for advancing a sheet at the front of the platen downwardly to cause the leading edge of the downwardly advanced sheet to move away 60 from said rolls, and means active on said leading edge to hold it in lateral conformity as it passes the front of the platen.

4. The combination of a platen, a rear-sheet introducing device adapted to direct the leading 65 edge of a sheet from the rear of the platen under the platen and around the front thereof, and a front-sheet introducing device having means for advancing another sheet downwardly from a position 70 above the platen, said front-sheet introducing device comprising means active upon the leading edge of the sheet for directing it down past the front of the platen.

5. The combination of a platen, a rear-sheet introducing device adapted to direct the leading 75 edge of a sheet from the rear of the platen under

the platen and around the front thereof, a front-sheet introducing device having means for advancing another sheet downwardly from a position above the platen, said front-sheet introducing device comprising means active upon the leading edge of the sheet for directing it down past the front of the platen, and means for independently line-spacing sheets introduced by both devices.

6. The combination of a platen, a rear-sheet 10 introducing device adapted to direct the leading edge of a sheet from the rear of the platen under the platen and around the front thereof, a front-sheet introducing device having means for advancing another sheet downwardly from a position above the platen, said front-sheet introducing device comprising means active upon the leading edge of the sheet for directing it down past the front of the platen, and means for independently line-spacing in either direction a sheet 20 introduced by either of said introducing devices.

7. The combination of a platen, a rear-sheet introducing device adapted to direct the leading edge of a sheet from the rear of the platen under the platen and around the front thereof, and a 25 front-sheet introducing device having friction roller means for advancing another sheet downwardly from a position above the platen, said front-sheet introducing device comprising means active upon the leading edge of the sheet for 30 directing it down past the front of the platen.

8. In an accounting machine, the combination of a platen, a front apron, a front-sheet introducing device comprising co-operative feed rolls for 35 downwardly advancing a sheet on said apron and guide means for directing the leading edge of the advancing sheet toward the front of the platen to align it and cause it to pass in such alignment down past the front of the platen, a rear apron, and a rear-sheet introducing device 40 comprising friction rolls co-operative with the platen to advance a sheet from said rear apron under and around the front of said platen, a part of said front sheet introducing device being capable of reverse operation to eject the front 45 sheet from the machine independently of the rear sheet.

9. In an accounting machine, the combination of a platen, a front apron, a front-sheet introducing device comprising co-operative feed rolls for 50 downwardly advancing a sheet on said apron and guide means for directing the leading edge of the advancing sheet toward the front of the platen to align it and cause it to pass in such alignment down past the front of the platen, a rear apron, and a rear-sheet introducing device 55 comprising friction rolls co-operative with the platen to advance a sheet from said rear apron under and around the front of said platen, a part of said front sheet introducing device being capable of reverse operation to eject the front sheet from the machine and the rear-sheet introducing device being capable of movement in either direction to move the rear sheet in either 60 direction without affecting the position of the front sheet.

10. In an accounting machine having a roller platen and friction feed roller means co-operative therewith for advancing a sheet from the rear around the under side and up past front 70 of the platen, means for independently supporting and feeding a sheet across the front of the platen comprising an apron above the platen, co-operative feed rolls between the apron and the platen for projecting the lower end of a sheet 75

on said apron downwardly in front of the first said sheet, and means for holding the leading edge of said lower end in substantial lateral alignment closely proximate the sheet at the 5 front of the platen as the action of the co-operative feed rolls continues.

11. In equipment of the character described, a platen, a roll located below and parallel with the platen, a plurality of tapes attached to said 10 roll and extending up past the platen, a roller located above and parallel with the platen, a frame pivotally supported to swing toward and away from said roller, winding means on said frame to which the upper ends of the tapes are attached, a roll on said frame adapted to hold a work-piece against said roller, means on one of the tapes forming a stop for the work-piece, and means for rotating said first mentioned roll and said winding means to move the tapes past 15 the platen.

12. In equipment of the character described, a platen, winding means located below the platen, a plurality of tapes attached to said winding means and extending up past the platen, a roller located above and parallel with the platen, a frame pivotally supported to swing toward and away from said roller, winding means on said frame to which the upper ends of the tapes are attached, means on one of the tapes forming a 20 stop for the work-piece, and means for actuating said winding means to move the tapes past the platen.

13. In equipment of the character described, a platen, a roll located below and parallel with the 25 platen, a plurality of tapes attached to said roll and extending up past the platen, a roller located above and parallel with the platen, a frame pivotally supported to swing toward and away from said roller, a shaft in said frame, winding means 30 on said shaft to which the upper ends of the tapes are attached, a spring normally holding said frame toward said roller, means on one of the tapes forming a stop for the work-piece, and means for rotating said roll and said winding 35 means to move the tapes past the platen.

14. In equipment of the character described, a platen, a roll located below and parallel with the platen, a plurality of tapes attached to said roll and extending up past the platen, a roller located 40 above and parallel with the platen, winding means to which the upper ends of the tapes are attached, means on one of the tapes forming a stop for the work-piece, a connection whereby said roll, said winding means and said 45 roller are caused to turn when one of said last mentioned three parts is turned, and means for turning one of said parts.

15. In equipment of the character described, a platen, a roll located below and parallel with the 50 platen, a plurality of tapes attached at their lower ends to said roll and extending upwardly past the platen, winding means above the platen to which the upper ends of the tapes are secured, means on one of the tapes forming a stop for the work-piece, and means for rotating said roll and said winding means to move the tapes past the platen. 55

16. In equipment of the character described, a platen, a plurality of tapes extending transversely of and in front of the platen, winding means 60 above the platen to which the upper ends of the tapes are secured, means on one of the tapes forming a stop for the work-piece, means for drawing the tapes downwardly, and means for actuating said winding means to draw the tapes upwardly. 70

17. In equipment of the character described, a platen, a roll located at one side of and parallel with the platen, a tape attached at one end to said roll and extending past the platen, winding means at the other side of the platen to which the other end of the tape is secured, means on the tape forming a stop for the work-piece, and means for rotating said roll and said winding means to move the tape past the platen. 75

18. In equipment of the character described, a platen, a roll located below and parallel with the platen, a plurality of tapes attached at their lower ends to said roll and extending upwardly past the platen, means above the platen to which the upper ends of the tapes are secured, means on one of the tapes forming a stop for the work-piece, and means for rotating said roll to move the tapes down past the platen. 10

19. In equipment of the character described, a platen, means for feeding a work-piece, lower end 20 first, down past the front of the platen, said means comprising winding means below the platen, winding means above the platen, a tape attached to both of said winding means, and means for simultaneously actuating said winding means, 25 one of said winding means being yieldingly connected to the actuating means.

20. In a machine of the character described, a transversely movable paper carriage, a rotary platen mounted in said carriage, a roll located in 30 the paper carriage below and parallel with the platen, a plurality of tapes attached to said roll and extending up past the front side of the platen, winding means in the carriage above the platen to which the upper ends of the tapes are 35 attached, and means for actuating said platen, roll and winding means to move a work-piece up and down past the platen. 40

21. In equipment of the character described, a platen, a tape located forwardly of the platen for moving a work-piece into position on the platen, 45 means on the side of the tape toward the platen to form a stop for the lower edge of the work-piece, and means for moving the tape transversely of the platen, with the work-piece lying between the tape and the platen, to move the work-piece into or out of position, while the platen is stationary. 50

22. In equipment of the character described, a platen, a tape for moving a work-piece into position on the platen, means on the tape forming a stop for the work-piece, and means for moving the tape longitudinally to move the work-piece into or out of position, the tape being connected to said moving means for edgewise adjustment 55 of the tape. 60

23. In equipment of the character described, a platen, a tape for moving a work-piece into position on the platen, means on the tape forming a stop for the lower edge of the work-piece, against 65 which stop the work-piece may be dropped, said stop being at the front of the platen when the tape is in initial position, and means for moving the tape to move the work-piece down between the tape and the platen and in front of the platen, while the platen is stationary. 70

24. In equipment of the character described, a cylindrical platen, means for feeding a work-piece up and down in front of the platen, mechanism for imparting line-space movements to the platen and to said front feed means, and means for suspending operation of said mechanism on the front feed means when the latter has moved the work-piece to a predetermined position. 75

25. In equipment of the character described, a platen, means for feeding a work-piece up and down in front of the platen, mechanism including a pawl and a ratchet wheel for imparting line-space movements to said front feed means, and means for automatically suspending operation of said pawl after a predetermined extent of movement of the work-piece.

26. In equipment of the character described, 10 a cylindrical platen mounted upon a fixed axis, a tape engaging the lower end of a ledger sheet for feeding the lower edge of the ledger sheet down past the front of the platen, to bring the 15 upper portion of the ledger sheet into printing position, said tape extending transversely of the platen, the work-piece lying between the tape and the platen, and means for longitudinally moving the tape, independently of the platen.

27. In equipment of the character described, 20 a rotary platen, front feed means, injector means for rapidly rotating the platen, and injector means for rapidly actuating the front feed means.

28. The combination of a platen, means for 25 directing a work-piece downwardly to the rear side of the platen, feed rolls beneath the platen for feeding said work-piece under and upwardly past the front of the platen, a paper table above the platen, and means independent of said feed 30 rolls for introducing a work-piece resting on said table, face forward and bottom-edge downward, down past the front of the platen, said means comprising a frame substantially as long as the platen, said frame being pivoted at its 35 ends on an axis located below and in front of the platen, and feed rolls between which the last-mentioned work-piece passes, one of said last-mentioned feed rolls being located between the lower edge of the paper table and the platen, and the coacting feed rolls being carried by said 40 frame.

29. The combination of a platen rotatable on a fixed axis, an apron behind the platen for 45 directing a work-piece downwardly to the rear side of the platen, feed rolls beneath the platen for feeding said work-piece under and upwardly past the front of the platen, and means independent of said feed rolls and including a plurality of tapes for introducing another work-piece down past the front of the platen, and maintaining said last-mentioned work-piece in 50 contact with the platen.

30. The combination of a platen rotatable on a fixed axis, an apron behind the platen for 55 directing a work-piece downwardly to the rear side of the platen, means for feeding said work-piece under and upwardly past the front of the platen, and means independent of the first-mentioned feeding means for introducing another work-piece down past the front of the platen, said independent means including a frame which is pivoted at its lower end at points forwardly of the platen and which is pivotally movable into and out of position to hold the second mentioned work-piece against the platen.

31. The combination of a platen rotatable on a fixed axis, means for directing a work-piece 60 downwardly to the rear side of the platen, means for feeding said work-piece under and upwardly past the front of the platen, and means independent of the first-mentioned feeding means for introducing another work-piece down past the front of the platen, the introducing means

comprising a frame pivoted to swing away from the platen into work-piece receiving position, and a plurality of tapes to guide, and to maintain said other work-piece in contact with said platen.

32. The combination of a platen rotatable on a fixed axis, means for directing a work-piece downwardly to the rear side of the platen, feed rolls beneath the platen for feeding said work-piece under and upwardly past the front of the platen, and means independent of said feed rolls for introducing another work-piece down past the front of the platen, the introducing means comprising a frame pivoted on an axis below and in front of the platen to swing toward and away from the platen, and feed rolls on said frame.

33. The combination of a rotary platen, means for directing a work-piece downwardly to the rear side of the platen, means for feeding 20 said work-piece under and upwardly past the front of the platen, means independent of said feed means for introducing another work-piece, bottom-edge foremost, down past the front of the platen, and lever-actuated means for rapidly operating said introducing means to inject 25 or eject the second-mentioned work-piece.

34. The combination of a roller platen, sheet-introducing means adapted to advance a sheet from the rear of the platen under and around the front thereof, another sheet-introducing means for advancing a sheet downwardly in front of the platen to lie in front of a rearwardly introduced sheet, the latter said means comprising cooperative friction feeding agents bearing on opposite faces of the sheet and disposed above a horizontal plane through the platen axis and means for maintaining the leading edge of the sheet in parallel alignment with the front of the platen as said edge reaches the platen 40 front in its advance from said friction feeding agents.

35. The combination of a roller platen, sheet-introducing means adapted to advance a sheet upwardly in front of the platen, a paper table 45 above the platen, another sheet introducing means for advancing a sheet from said paper table downwardly past the front of the platen comprising cooperative friction feeding agents presenting a bite in position to receive a sheet 50 positioned against said table and means for maintaining the leading edge of the sheet in parallel alignment with the front of the platen as said edge reaches the platen front in its advance from said friction feeding agents.

36. The combination of a roller platen, sheet-introducing means adapted to advance a sheet from the rear of the platen under and around the front thereof, another sheet-introducing means for advancing a sheet downwardly in 60 front of the platen to lie in front of a rearwardly introduced sheet, the latter said means comprising cooperative friction feeding agents bearing on opposite faces of the sheet and disposed above a horizontal plane through the platen 65 axis and means for maintaining the leading edge of the sheet in parallel alignment with the front of the platen as said edge reaches the platen front in its advance from said friction feeding agents, the aforesaid introducing means for the sheets having provision for selectively relatively 70 moving the sheets in either direction.

OSCAR J. SUNDSTRAND.
